UNITED STATES PATENT OFFICE.

WHEELER H. VIBBER, OF NEW LONDON, CONNECTICUT, ASSIGNOR TO THE GILLETTE-VIBBER CO., OF NEW LONDON, CONNECTICUT, A CORPORATION.

ELECTRIC-INSTALLATION MOLDING-BOX.

No. 899,637.

Specification of Letters Patent. Patented Sept. 29, 1908.

Application filed June 11, 1907. Serial No. 378,349.

To all whom it may concern:

Be it known that I, WHEELER H. VIBBER, a citizen of the United States, residing at New London, in the county of New London and State of Connecticut, have invented a new and useful Improvement in Electric-Installation Molding-Boxes, and I do hereby declare the following, when taken in connection with the accompanying drawings and the letters of reference marked thereon, to be a full, clear, and exact description of the same, and which said drawings constitute part of this specification, and represent, in—

Figure 1 a reverse plan view of one form which the body of my improved electric installation molding-box may assume, this particular box-body having one peripheral molding-end recess and being therefore adapted for use in conjunction with a single strip of molding. Fig. 2 a corresponding view of a box-body having two peripheral molding-end recesses located opposite each other, one of them containing two insulating bushings. Fig. 3 a corresponding view of the box-body having two peripheral molding-end recesses located at a right angle to each other. Fig. 4 a corresponding view of the box-body having three peripheral molding-end recesses. Fig. 5 a corresponding view of the box-body having four peripheral molding-end recesses. Fig. 6 a view in side elevation of the box-body shown by Fig. 1 as provided with a flat cover. Fig. 7 a plan view of the cover shown by Fig. 6. Fig. 8 an edge view thereof. Fig. 9 a view on a reduced scale of the box-body of Fig. 1 shown in conjunction with a cup-shaped or chambered cover having a wide flange to adapt it to form a bearing for canopies varying in diameter and showing the application to the said cover of the stem of a lamp-fixture.

My invention relates to an improvement in electric installation molding boxes, the object being to produce a compact, effective and convenient box constructed with particular reference to securing a neat and workmanlike junction between the box and the molding or moldings leading to it.

With these ends in view my invention consists in an electric installation molding box having certain details of construction and combinations of parts as will be hereinafter described and pointed out in the claims.

In carrying out my invention as shown in

Figs. 1 and 6, the circular box-body 2 is formed in its periphery with a single shallow, rectangular molding-end recess 3 adapted in width and depth to receive the end of a strip of wooden molding such as is commonly used in the installation of electric wires upon the surface of a ceiling or upon a side wall the said recess being open on the side closed by the cover of the box. The inner wall 4 of this recess is formed with two corresponding vertical U-shaped ports 5 from which the wires are led from the molding into the interior of the box these ports being arranged to be open on the side closed by the cover of the box. By preference these ports will be occupied by insulating bushings 6 as shown in Fig. 2, though they may be omitted. The inner walls of the recesses may be formed with one, two or three ports 5 as desired. The said walls 4 are located at a right angle to the plane of the body, form abutments for the ends of the molding strips, provide means for carrying insulating bushings and preserve the structural integrity of the body.

As shown the box-body is formed with four screw holes 7 by means of which it is fastened to the ceiling, with an inwardly projecting lug 8 having a threaded screw hole 9 for the reception of one of the screws by means of which the cover is secured in place, and with a threaded screw hole 10 for another screw for the same purpose. The screws are not shown.

The box-body 11 shown by Fig. 2 is provided with two molding-end recesses 3 located opposite each other, while the box-body 12 shown by Fig. 3 has two molding-end recesses located at a right angle to each other. The box-body 13 of Fig. 4 has three such recesses, and the box-body 14 of Fig. 5 four of them. It is enough to say in this connection that the number of recesses will depend upon the number of moldings employed.

My improved box-body may have any suitable cover applied to it. In Figs. 6, 7 and 8 I have shown a flat circular cover 15 provided with screw holes 16 and 17 and furnished upon its upper face with a circular series of beveled positioning lugs 18 located just within its edge so as to collectively have the function of a retaining-flange. These lugs are spaced so as to enter the molding-end recesses 3 in pairs as shown by Fig. 6 and

partially close the open ends of the ports 5 and are beveled so as to fit the bevels of ordinary molding.

In the construction shown by Fig. 9 the box 19 is provided with a cup-shaped or chambered cover 20 having a flange 21 considerably larger in diameter than the box to adapt it to form a bearing or seat for canopies varying considerably in diameter. This cover is furnished upon its upper face with beveled lugs 18 like those already referred to, and formed with a centrally arranged threaded opening 22 into which the stem 23 of a lamp-fixture is screwed, it being designed to have a lamp-fixture carried by the cover even as the cover is carried by the box-body.

I claim:

1. An electric installation molding-box body formed in its periphery with one or more shallow, rectangular molding-end recesses open on the side closed by the cover of the box and each separated from the interior of the body by a wall containing one or more U-shaped ports open on the side closed by the cover of the box, in combination with a box-cover adapted to close the said recesses and ports as described.
2. An electric installation molding-box body formed in its periphery with one or more shallow, rectangular molding-end recesses open on the side closed by the cover of the box and each separated from the interior of the body by a wall containing one or more U-shaped ports open on the side closed by

the cover of the box; in combination with one or more insulating bushings located at the bottom of the said recess or recesses and in the said port or ports and a cover adapted to close the said recesses and ports as described.

3. An electric installation molding-box body formed in its periphery with one or more shallow, rectangular molding-end recesses open on the side closed by the cover of the box, in combination with a cover provided with a series of positioning lugs arranged to enter the said recesses and engage with the end walls thereof, and the said lugs being beveled to fit the bevels of the molding.

4. The combination with a circular electric installation molding-box body formed in its periphery with one or more shallow, rectangular molding-end recesses open on the side closed by the cover of the box; of a circular box cover adapted to have a lamp-fixture attached directly to it and formed with a wide circular flange to act as a bearing for canopies varying in diameter, the said flange being larger in diameter than the diameter of the box-body.

In testimony whereof, I have signed this specification in the presence of two subscribing witnesses.

WHEELER H. VIBBER.
